To all whom it may concern:

Be it known that I, PIERRE CHARLES CHAMBELLAN, a citizen of France, residing at West Hoboken, New Jersey, have invented a new 5 and original Design for Carpets, of which the following is a specification, reference being had to the accompanying photograph, which forms a part of the same.

The accompanying photograph is a face 15 view of a carpet, showing my new design.

My design consists of a body A and a border B. The body A is composed of a large group of flower and leaf forms partly sur-

rounded by curving branches somewhat spiral in form. The border B is composed of groups 20 of flower and leaf forms and spiral branching arms and ornamental inner and outer margins.
